UNITED STATES PATENT OFFICE.

LAURENCE A. HAWKINS, OF SCHENECTADY, NEW YORK, ASSIGNOR, BY MESNE ASSIGNMENTS, TO THE UNION SWITCH AND SIGNAL COMPANY, A CORPORATION OF PENNSYLVANIA.

BLOCK-SIGNAL SYSTEM.

1,157,104.

Specification of Letters Patent. Patented Oct. 19, 1915.

Application filed August 6, 1906. Serial No. 329,347.

To all whom it may concern:

Be it known that I, LAURENCE A. HAWKINS, a citizen of the United States, residing at Schenectady, county of Schenectady, State of New York, have invented certain new and useful Improvements in Block-Signal Systems, of which the following is a specification.

My invention relates to block signal systems for electric railways, and its object is to provide a safe and efficient system possessing certain advantages not heretofore obtained.

In block signal systems for electrically-operated railways it is desirable to use the rails not only for the signal circuits, but also as a return conductor for the power-current. Various arrangements have been proposed heretofore for permitting the rails to perform both functions. Since it has heretofore been considered necessary that each block circuit should be insulated from the adjacent blocks, as far as the signal current is concerned, numerous devices, such as choke-coils, inductive bonds, and special arrangements of connections, have been devised to transmit the power-current from one block to another, while preventing the flow of the alternating current employed for the signal circuits. All of these devices are expensive and inefficient, since they must furnish sufficient reactance to prevent the flow of signal current from block to block and at the same time transmit the power-current without saturating the magnetic circuit of the devices.

One object of my invention is the arrangement of the signal circuits so that the rails may be made continuous, as in an electric railway not employing block signals. By my invention the insulating joints between blocks are done away with, and the rails may be bonded or welded as in the usual street railway practice.

In the practice of my invention I provide, in combination with a railway having both rails conductively continuous for all currents, signals for the blocks, controlling circuits therefor, sources of alternating current connected across the rails at intervals, track relays supplied with current from the rails and having their contacts included in the signal controlling circuits, and means for preventing the operation of each relay ex-

cept by current from one of said sources only, this means, in the arrangement illustrated in the drawing, consisting of a second winding on the relay coöperating with the track winding to produce the relay torque and supplied with current of a character to produce a torque in the relay only when the track winding is supplied with current from the proper source.

In the embodiment of my invention which I have disclosed herein I employ for the track-circuits a plurality of sources of current differing in character from the power-current and from each other connected to the track-rails at intervals corresponding to the length of a block and employ for the different blocks relays responsive to current of one character but not to that of another. By means of this combination the relays may be arranged to operate in the same manner as though the several blocks were wholly insulated from each other.

In arranging the several parts of the system in its preferred form, my invention further comprises certain relative arrangements of current sources and relays. Broadly stated, I connect the sources of current across the rails at intervals and group the relays in pairs placed between each two adjacent sources and connect the relay contacts so that each relay controls the signal guarding the portion of track between the relay and one adjacent source. Each portion of track between adjacent sources is effectively guarded by a pair of relays, one for the track-length from one source to the relays, and the other for the track-length from the relays to the other source. One relay of each pair is deenergized by a car at any point between it and one adjacent source and the other relay by a car at any point between it and the other adjacent source. In this preferred form of the system, each signal is preferably controlled by two relays.

My invention will be better understood from a consideration of the following description taken in connection with the accompanying drawings, in which—

Figure 1 is a diagram illustrating my invention in its simplest forms; and Fig. 2 illustrates the arrangement which I prefer to employ.

In Fig. 1, A represents the two rails of the track, which are both continuous, as in the

usual street railway practice, so as to form a return-conductor for the power-current. B represents the supply conductor for the power-current, such as a third-rail or trolley wire, which is connected to one terminal of the source of power-current indicated at C. The other terminal of the source may be connected to the track-rails A through a differential choke-coil c. The generator C may supply any suitable kind of power-current such as direct-current or low-frequency alternating-current. D¹, D² and D³ represent alternating-current generators, preferably of high frequency; the current delivered by the three generators being of different frequency. d, d¹, d² and d³ represent supply-conductors from these generators extending along the track. Conductor d is a common return-conductor for all these frequencies. E¹, E², etc., represent transformers which have their primaries connected to the supply-conductors and their secondaries connected across the track-rail. It will be noticed that adjacent transformers are connected to supply-conductors of different frequencies,—that is, the transformer E¹ supplies to the rails a current of the frequency delivered by the generator D¹, while the transformer E² delivers current of the frequency of generator D². The transformers are preferably arranged with an air-gap in the magnetic circuit, as indicated, in order to prevent saturation by the flow of power-current, such as might arise from defective bonding. A small ohmic resistance e may also be inserted in the secondary of the circuit of the transformers, in order to keep down the flow of power-current. This resistance e, and also the air-gaps in the magnetic circuit of the transformer, serve to prevent the transformer from giving too heavy a current when short-circuited by a train standing directly across the secondary terminals. The distance between adjacent transformers corresponds to the desired length of a block. Relays F¹, F², etc., are connected across the rails at the entrance of the several blocks. These relays are each arranged to respond to only one frequency, and for this purpose are provided with two coöperating windings,—one connected across the rails and the other supplied independently of the rail-circuit with current from the supply conductors. I have shown the relays as of the type having one fixed and one movable coil, but it will be understood that the illustration is purely diagrammatic, and that any other form of selective relay may be used. The stationary winding of the relay F¹ is shown connected across the supply-conductors d and d¹, so that although its movable or track-coil is traversed by current from each of the transformers E¹, E² and E³, it responds only to the current delivered by the transformers E¹. The

relay F² similarly responds to the current delivered by transformer E². A non-inductive resistance f may be placed in series with the track-coils of the relays so as to prevent an excessive flow of power-current through the relays, due to faulty bonding. The relay F¹ controls a signal G¹, which protects the portion of the track between the transformers E¹ and E². The signal-actuating mechanism is illustrated diagrammatically, and in practice any well known form of signal-operating mechanism may be employed. H represents a car or train which has just entered the portion of track between the transformers E³ and E⁴.

It will be perceived that since the rails are continuous, a portion of the current from each source will pass beyond the block and through other signaling devices so that not only is there a certain waste due to this leakage-current, but also each relay must be at a sufficient distance from every source of current of the character to which it responds, except the source from which its current properly comes, to prevent its being actuated from any other source. Steel rails, however, offer a comparatively high impedance to high-frequency alternating-currents, and by employing such currents for the signal-circuits I am enabled both to reduce the leakage-current to a reasonable amount, and also to reduce the kinds of current employed to a small number. It will be further seen that the length of a block is not absolutely determinate as in the ordinary arrangement, since the rails are continuous and the shunting as a train approaches a relay is gradual. In my system a signal for one block is set at danger a short time before the signal for the preceding block has cleared. In other words, there is an over-lap which is, to a certain extent, indeterminate. I have found, however, that by the use of a high-frequency signal-current, so as to obtain a high rail-impedance, and by the proper proportioning of the signal devices, the over-lap may be made so short and so definite as to be practically negligible.

With the above explanation in mind, the operation of the system shown in Fig. 1 will be clear. With the car H in the position shown, the rails between the transformer E³ and relay F³ are short-circuited. Consequently, track-coil of relay F³ is deenergized so as to open the circuit of signal G³ and allow the signal to go to danger. This signal will obviously remain at danger as long as the car is between transformer E³ and relay F³,—that is as long as the car is in the block guarded by the signal. When the car approaches the relay F², it gradually shunts the current from this relay until, when a certain point is reached, the voltage across relay F² will be lowered to such

an amount as to put the signal G^2 at danger. The signal G^2 consequently goes to danger some time before the car enters the block between relay F^2 and transformer E^2 , and this signal, in accordance with the usual practice, which arranges the signal at such a point that it will not go to danger until the locomotive has passed, should be placed a certain distance in front of the relay F^2 .
 10 This distance forms the over-lap over the system. That is, while the train is within this distance both signals G^2 and G^3 will stand at danger. The length of this overlap obviously depends upon the impedance of the rail-circuit as compared to the impedance of the relay-circuit, and the regulation of the transformer supplying the relay. Even with the arrangement shown in Fig. 1, this over-lap may be sufficiently short and 15 determinate for commercial purposes, and with improved arrangements, such as will be hereinafter described, the over-lap may be made exceedingly short and definite; that is, less than one hundred yards.
 20 25 It will be seen that the transformers E^1 and E^4 , which are the nearest transformers connected to the same supply-conductors, are oppositely connected so as to impress on the track voltages one hundred and eighty degrees out of phase. The purpose of this connection is to increase the safety of the system. With this connection, whatever current from transformer E^4 reaches relay F^1 will tend to put it at danger instead of holding it at clear position. The nearest transformer, other than transformer E^1 , which can supply current to relay F^1 of the proper frequency and phase to move to clear position, is three blocks from transformer E^4 ,—
 30 that is, five blocks away from relay F^1 . Consequently, no appreciable amount of effective current can possibly reach relay F^1 from any source except its own transformer. It will furthermore be noted that the central 35 point of the block between transformer E^2 and relay F^2 is equi-potential with respect to transformers E^1 and E^4 when oppositely connected, as shown. Consequently, a train in the middle of this block will have no effect on the relay F^1 , and begins to shunt it only after passing the central point. The 40 reverse connection of transformers E^1 and E^4 of course, produces a certain leakage-current which finds a path through the secondaries of the two transformers in series. This 45 leakage-current, even with the arrangement of Fig. 1, need not be excessive, if the impedance of the transformer secondaries and of the relay track-coils are comparatively 50 low with respect to the rail impedance, and can be greatly reduced by other connections of transformers and relays, which will be described hereafter.
 55 60 65 The simple arrangement described in Fig. 1 has certain disadvantages. In the first

place, it will be seen that relay F^1 is connected directly in shunt to transformer E^2 , while it is a block away from transformer E^1 . Consequently, this relay is traversed by a useless current, which is larger than the useful current which flows through it. In the second place, as a train approaches a relay and begins to shunt it, the increased current flowing from the transformer, produces an increased drop on the rails 75 between the transformer and relay, so that the fall of current in the relay is greater and the over-lap is longer than would be the case, if the rail impedance of a whole block were not between the transformer and the approaching train. In the third place, at least three different kinds of current must be employed for the signal circuits. These objections, while not affecting the operativeness of the system, decrease its 80 commercial efficiency, and may all be removed by the modified arrangement shown in Fig. 2. In this arrangement two relays are employed for each block, and are connected at the center of the block; the two relays in each pair responding respectively to the currents from the two transformers at the ends of the block. The two relays are arranged jointly to control the signal for the block, as by having their armature contacts 85 placed in series with each other in the signal-circuit. The track-coils of the relays may be connected in any suitable manner, for example in parallel as shown in the figure. In Fig. 2 only two different frequencies D^1 and D^2 are employed.
 90 95 100

The operation of the system is as follows: with the car H in the position shown, the rails between transformer E^4 and relay F^6 are short-circuited so that this transformer 105 can supply no current to this relay. The current from the transformer E^3 has no effect on the relay F^6 , so that this relay is de-energized and drops its armature, as shown, moving signal G^3 to danger. As the train 110 H proceeds in the direction of the arrow, it gradually shunts the current supplied by transformer E^3 around the relays. Consequently, at some point before the train reaches the relays, relay F^5 will also have 115 dropped its armature, thereby making a second break in the signal-operating mechanism G^3 . Obviously, relay F^5 can not again pick up its armature until after the train has passed a certain distance to the other 120 side of transformer E^3 . As the train approaches transformer E^3 , however, it draws from the transformer a continually larger current, which reduces the potential impressed by this transformer on the track, 125 and consequently reduces the amount of current supplied by this transformer to relay F^4 . For instance, if the relay F^4 is designed so as to drop its armature when the voltage across the terminals is reduced to one-fourth 130

its normal value, the signal G^2 will go to danger when the train reaches a point near enough to the transformer E^3 to cause it to give a sufficient current to lower the voltage impressed by it on the track to one-fourth its normal value. The distance of this point from the transformer will obviously depend, first upon the impedance of the track-rails, which, in series with the wheels of the train, 10 form the short-circuit for the transformer, and second, upon the regulation of the transformer, or in other words, upon the amount of voltage used up in inductive and ohmic drop in its own windings and ohmic drop 15 in the resistance e . The higher the impedance of the rails, and the lower the impedance of the secondary circuit of the transformer the nearer must the train approach the transformer E^3 in order to pull the voltage down a given amount. By using a comparatively high frequency, such, for instance, as three hundred cycles, so as to give a high impedance to the rails, the relay and transformer may readily be designed so that 20 the relay will not drop out until the train is within less than one hundred yards of the transformer. This one hundred yards or less, forms the overlap of the system, since when the train is this distance from the 25 transformer E^3 , the signal G^2 will go to danger on account of relay F^4 letting go its armature. Signal G^3 is meanwhile still at danger, since, although relay F^6 will by this 30 time have picked up its armature, relay F^5 will still be in open-circuit position, as the 35 train is between this relay and the transformer E^3 , which supplies it. Thus both signals G^2 and G^3 are at danger while the train is passing transformer E^3 . Relay F^5 will 40 not pick up its armature until the train has passed transformer E^3 a sufficient distance to allow the voltage supplied by transformer E^3 to the track to rise a sufficient amount for this purpose. 45 The signal G^2 should, in accordance with the usual practice, be placed sufficiently far back of transformer E^3 so that it will not go to danger until after the locomotive has passed it. As stated above, this distance 50 may be not more than one hundred yards, and since the signal is sure to go to danger before the train is directly over the terminals of transformer E^3 , there is no chance that the train can have passed the signal any 55 distance with the signal still at clear. In other words, the indeterminateness of the over-lap may be made so slight by the proper design as to be negligible.

60 The location of the transformers at the entrances to the blocks and the relays at points beyond, so that an approaching train reaches the transformer first, assists materially in making the over-lap short and definite, for the reasons already explained.

65 The only source of variation in the length

of this overlap is variation of impedance in the rails. The power-factor of the rail-circuit at a high frequency is comparatively low, and the power-factor of the secondary-circuit of the supply transformers is preferably made practically the same, so that variation in the length of track included in circuit as a train approaches a transformer produces a direct proportional variation in the current flow from the transformer. Consequently, a variation in ohmic resistance in the track, due to defective bonding or to temperature changes, has a comparatively slight effect on the impedance of the track, and consequently upon the length of the 70 overlap, and the ohmic factor of the track 75 impedance is the only variable.

It has been seen that each signal will go to danger shortly before the train passes the adjacent transformer, and will remain 80 at danger until the train has passed a certain distance beyond the next transformer. Also a broken rail anywhere between the two 85 transformers will put the signal at danger, since it will cut off current of one frequency 90 from the relays, so as to deenergize one of them.

95 It will be seen that the current from the secondary of each transformer divides, part passing in each direction. On reaching the relays, part of the current passes through the relays and part tends to pass beyond the relays and to return through the other signal devices connected across the rails beyond the relays. If, however, the impedance of 100 the relay-circuit from rail to rail is made small compared to the impedance of the rails of a block, the amount of current which passes beyond the relays will be comparatively small. Furthermore, it will be noticed 105 that in Fig. 2, the adjacent transformers which are connected to supply-conductors of the same frequency, such, for instance, as 110 transformers E^1 and E^2 are oppositely connected, in the same manner as in Fig. 1, so 115 that any small amount of current which may reach relay F^4 from transformer E^1 produces a torque in the opposite direction to the normal, so that this small leakage-current is on the side of safety. In fact, 120 when a train is directly across the terminals of transformer E^3 , so that no current from that transformer is passing to relay F^4 , a very small leakage-current reaches the relay 125 F^4 from transformer E^1 , which tends to actually drive it toward open-circuit position. Thus, although this leakage-current is ordinarily too small to be of any appreciable effect, it is of some assistance in preventing the relay from sticking in closed-circuit position when shunted by a train.

130 By comparing Figs. 1 and 2, it will be seen that while the distance between adjacent transformers of the same frequency in Fig. 1 is only three times the distance be-

tween each transformer and its relay, the ratio of these distances in Fig. 2 is four to one, so that the arrangement of Fig. 2 with only two frequencies reduces the proportionate amount of current that flows through both transformer secondaries in series as compared with three frequencies in the arrangement of Fig. 1, or looked at another way, each relay in Fig. 1 is a block 10 away from its own transformer, and only twice that distance from another transformer, which tends to send a reverse current through it; while in Fig. 2 each relay is three times as far away from the nearest 15 transformer that tends to send a reverse current through it, as it is from its own transformer. In fact, by the arrangement of Fig. 2, the same effect as regards this leakage-current is obtained as would be obtained by 20 using four frequencies, in Fig. 1; while three frequencies, with the arrangement of Fig. 2, would give the same effect as regards leakage-current, as six frequencies arranged as in Fig. 1,—that is, a wholly negligible effect. 25 Two frequencies, however, if arranged as in Fig. 2, are sufficient for a commercially efficient system.

It will be noted that in the arrangement of Fig. 2, the transformers and the connections 30 across the rails between them form with the rails a pair of closed track circuits between each two transformers, each transformer being common to two adjacent track circuits, and that each track circuit has an independent 35 set of relay contacts included in a signal-controlling circuit and operating to put at danger the signal guarding the portion of track over which the track circuit extends upon a failure, from any cause, of current 40 at the far end of the track circuit from the transformer at the other end.

The arrangement of Fig. 2 is not the only modification of Fig. 1, which may be made 45 in order to improve its efficiency. It is, however, a particularly advantageous arrangement for long blocks since each relay is only half a block away from its transformer, so that a low voltage may be used for the signal 50 circuits in spite of the high impedance of the rails. Other modifications will readily occur to those skilled in the art. Furthermore, although I have illustrated my invention with one only one track arranged for 55 trains going in one direction, it is equally applicable to any number of tracks, and for trains going in one or both directions. Consequently, I do not desire to limit myself to the particular construction and arrangement 60 of parts here shown, but aim in the appended claims to cover all modifications which are within the scope of my invention.

What I claim as new, and desire to secure by Letters Patent of the United States, is,—

1. In combination with an electric railway

having both rails conductively continuous for all currents, a plurality of sources of current connected at intervals across the rails, the current from adjacent sources differing in character from each other and 70 from the power-current, track-relays connected across the rails each responsive to current of one character and not to that of another, and signals controlled by said relays. 75

2. In combination with an electric railway having both rails conductively continuous for all currents, a plurality of sources of high-frequency alternating-current connected at intervals across the rails, the currents from adjacent sources differing in character, track-relays connected across the rails each responsive to current of one character and not to that of another, and signals controlled by said relays. 80

3. In combination with an electric railway having both rails conductively continuous for all currents, a plurality of sources of alternating-current connected at intervals across the rails, adjacent sources being of 90 different frequency, track-relays connected across the rails each responsive to alternating-current of only one frequency, and signals controlled by said relays. 85

4. In combination with an electric railway having both rails conductively continuous for all currents, a plurality of sources of high-frequency alternating-current connected at intervals across the rails, track-relays connected across the rails at points 95 intermediate adjacent sources, there being two relays for each source and controlled thereby, and signals controlled by said relays, one signal being controlled by a pair of adjacent relays. 100

5. In combination with an electric railway having both rails conductively continuous for all currents, two sources of alternating-currents of different frequencies connected across the rails a distance apart, a block 110 signal for the portion of track between said sources, and signal-controlling means connected across the rails at a point between said sources and arranged to put said signal at danger upon a failure of current from either of said sources. 115

6. In combination with an electric railway having both rails conductively continuous for all currents, two sources of alternating-currents of different frequencies connected across the rails a distance apart, two relays connected across the rails at a point between said sources each responsive to one frequency only, and a signal controlled by the joint action of said relays. 120

7. In combination with an electric railway having both rails conductively continuous for all currents, two sources of alternating-currents of different frequencies connected across the rails a distance apart, two 130

relays connected across the rails at a point between said sources each responsive to one frequency only, a signal, and a controlling circuit therefor including the contacts of both relays in series.

8. In combination with an electric railway having both rails conductively continuous for all currents, two sources of current of different character connected across the rails a distance apart, two relays connected across the rails at a point between said sources each responsive to current of one character and not to that of another, and a signal controlled by the joint action of said relays.

9. In combination with an electric railway having both rails conductively continuous for all currents, a plurality of sources of current connected at intervals across the rails, the currents from adjacent sources differing in character from each other and from the power-current, track-relays connected across the rails each responsive to current of one character and not to that of another, and signals each controlled by the joint action of a plurality of relays.

10. In combination with an electric railway having both rails conductively continuous for all currents, a plurality of sources of alternating-current connected at intervals across the rails, adjacent sources being of different frequency, track-relays connected across the rails each responsive to alternating-current of only one frequency, and signals each controlled by the joint action of a plurality of relays.

11. In combination with an electric railway having both rails conductively continuous for all currents, a plurality of sources of current connected at intervals across the rails, the currents from adjacent sources differing in character from each other and from the power-current, track-relays each having two coöperating windings, one connected across the rails and the other supplied independently of the rail-circuit with current of the same character as that from one of the adjacent sources, and signals controlled by said relays.

12. In combination with an electric railway having both rails conductively continuous for all currents, a plurality of sources of current connected at intervals across the rails, the currents from adjacent sources differing in character from each other and from the power-current, track-relays each having two coöperating windings, one connected across the rails and the other supplied independently of the rail circuit with current of the same character as that from one of the adjacent sources, and signals each controlled by the joint action of a plurality of relays.

13. In combination with an electric railway having both rails conductively continuous for all currents, a plurality of sources

of alternating-current connected at intervals across the rails, adjacent sources being of different frequency, track relays each having two coöperating windings, one connected across the rails and the other supplied independently of the rail-circuit with alternating-current of the same frequency as one of the adjacent sources, and signals controlled by said relays.

14. In combination with an electric railway having both rails conductively continuous for all currents, a plurality of sources of alternating-current connected at intervals across the rails, adjacent sources being of different frequency, track-relays each having two coöperating windings, one connected across the rails and the other supplied independently of the rail-circuit with alternating-current of the same frequency as one of the adjacent sources, and signals each controlled by the joint action of a plurality of said relays.

15. In combination with an electric railway having both rails conductively continuous for all currents, two sources of alternating-currents of different frequencies connected across the rails a distance apart, two relays each having one winding connected across the rails at a point between said sources and a second coöperating winding supplied independently of the rail-circuit, the currents in the second windings of the two relays corresponding in frequency respectively to the two sources, and a signal controlled by the joint action of said relays.

16. In combination with an electric railway having both rails conductively continuous for all currents, a plurality of sources of alternating-current connected across the rails, adjacent sources being of different frequency and each source being oppositely connected relatively to the nearest source of the same frequency, track relays each having one winding connected across the rails and a second coöperating winding supplied independently of the rail-circuit with current of the same frequency as one adjacent source, and signals controlled by said relays.

17. In combination with an electric railway having both rails conductively continuous for all currents, supply conductors carrying alternating-currents of different frequencies, transformers having their secondaries connected at intervals across the rails and their primaries connected alternately to supply conductors of different frequencies, track-relays each responsive to currents of only one frequency, and signals controlled by said relays.

18. In combination with an electric railway having both rails conductively continuous for all currents, supply-conductors carrying alternating-currents of different frequencies, transformers having their secondaries connected at intervals across the

5 rails and their primaries connected alternately to supply-conductors of different frequencies, track-relays each having two co-operating windings, one connected across the rails and the other to the supply conductors, and signals controlled by said relays.

10 19. In combination with an electric railway having both rails conductively continuous for all currents, supply-conductors carrying alternating-currents of different frequencies, transformers having their secondaries connected at intervals across the rails and their primaries connected alternately to supply-conductors of different frequencies, track-relays arranged in pairs at 75 points midway between each two transformers, each having a winding connected across the rails and a second co-operating winding connected to the supply-conductors, the two 80 relays being connected to conductors of different frequencies, and a block-signal controlled by the joint action of each pair of relays.

20 20. In combination with an electric railway having both rails conductively continuous for all currents, supply conductors carrying alternating currents of different frequencies, transformers having their secondaries connected at intervals across the 70 rails and their primaries connected alternately to supply-conductors of different frequencies and each transformer being oppositely connected relatively to the nearest transformer connected to the same supply conductors, track-relays each responsive to currents of only one frequency, and signals controlled by said relays.

25 21. In combination with an electric railway having its rails connected to form a plurality of continuous return-conductors for the power-current, a plurality of sources of alternating-current across the track-rails, adjacent sources being of different frequency, track-relays connected across the 85 rails each responsive to alternating-currents of only one frequency, and signals controlled by said relays.

30 22. In combination with an electric railway having its rails connected to form a plurality of continuous return-conductors for the power-current, a plurality of sources of alternating-current connected across the track-rails adjacent sources being of different frequency, track-relays each having two co-operating windings, one connected across the rails and the other supplied independently of the rail-circuit with current of the same frequency as one of the adjacent sources, and signals controlled by said relays.

35 23. In combination with an electric railway, a plurality of sources of alternating-current connected across the rails, the rails being connected to form continuous conductors for all currents between said sources

40 and adjacent sources being of different frequency, track-relays connected across the rails each responsive to alternating-currents of only one frequency, and signals controlled by said relays.

45 24. In combination with an electric railway, a plurality of sources of alternating-current connected across the rails, the rails being connected to form continuous conductors for all currents between said sources 75 and adjacent sources being of different frequency, track-relays each having two co-operating windings, one connected across the rails and the other supplied independently of the rail-circuit with current of the same 80 frequency as one of the adjacent sources, and signals controlled by said relays.

50 25. In combination with an electric railway having both track rails continuous for the return of power-current, a plurality of sources of current differing in character from the power-current and from each other connected to the track-rails at intervals corresponding to the length of the block, and track relays for the several blocks responsive to current of one character but not to that of another.

55 26. In combination with an electric railway having both track-rails conductively continuous for all currents, a plurality of sources of current differing in character from the power-current and from each other connected across the track-rails at intervals, track-relays connected in pairs across the rails approximately midway between two 95 adjacent sources each responsive to current of one character and not to that of another, and signals controlled by said relays.

60 27. In combination with an electric railway having both track-rails continuous, a 105 plurality of sources of alternating-current of different frequencies connected across the track-rails at intervals, track-relays connected in pairs across the rails approximately midway between two adjacent sources, one relay of each pair being responsive only to the frequency of one adjacent source and the other relay being responsive only to the frequency of the other adjacent source, and signals controlled by said relays.

65 28. In a block signal system, in combination with a railway having both rails conductively continuous for all currents, signals for the blocks, signal controlling circuits, sources of alternating current connected 110 across the rails at intervals adjacent sources being of different character and track relays grouped in pairs, one pair being placed between each two adjacent sources, and each relay having its contacts included in a circuit controlling the signal which guards the portion of track between said relay and one adjacent source.

70 29. In a block signal system, in combination with a railway having both rails con- 115

ductively continuous for all currents, signals for the blocks, signal controlling circuits, sources of alternating current connected across the rails at intervals corresponding to the length of a block, adjacent sources being of different character and track relays grouped in pairs, one pair being placed between each two adjacent sources and each relay having its contacts included in a circuit controlling the signal which guards the portion of track between said relay and one adjacent source, each of said signals being controlled by two track relays.

30. In a block signal system, in combination with a railway having both rails conductively continuous for all currents, signals for the blocks, signal controlling circuits, sources of alternating current connected across the rails at intervals, adjacent sources being of different character and relays grouped in pairs, one pair being placed between each two adjacent sources, each relay having a winding supplied with current from the rails and a second coöperating winding supplied with current independently of the track circuits and each relay having its contacts included in a circuit controlling the signal which guards the portion of track between said relay and one adjacent source.

31. In a block signal system, in combination with a railway having both rails conductively continuous for all currents, signals for the blocks, signal controlling circuits, sources of alternating current connected across the rails at intervals corresponding to the length of a block, adjacent sources being of different character and relays grouped in pairs, one pair being placed between each two adjacent sources, each relay having a winding supplied with current from the rails and a second coöperating winding supplied with current independently of the track circuits, and each relay having its contacts included in a circuit controlling the signal which guards the portion of track between said relay and one adjacent source, each signal being controlled by two track relays.

32. In combination with a railway having both rails conductively continuous for all currents, a block signal system, comprising signals for the blocks, controlling circuits therefor, sources of alternating current connected across the track rails at intervals, adjacent sources being of different character, connections from one rail to the other between adjacent sources, each set of connections forming with the adjacent sources and the rails between them a pair of closed track circuits, each of said sources being common to two adjacent track circuits, and an independent set of signal controlling contacts for each track circuit, means interposed in said connections and controlling the contacts to cause the said contacts for each track cir-

cuit to open a controlling circuit for the signal guarding the portion of track, over which said track circuit extends, upon a failure of current at the far end of said circuit from the source at the other end.

33. In combination with a railway having both rails conductively continuous for all currents, a block signal system, comprising signals for the blocks, controlling circuits therefor, sources of alternating current connected across the track rails at intervals, adjacent sources being of different character, connections from one rail to the other between adjacent sources, each set of connections forming with the adjacent sources and the rails between them a pair of closed track circuits, each of said sources being common to two adjacent track circuits, and an independent set of signal controlling contacts for each track circuit, means interposed in said connections and controlling the contacts to cause the said contacts for each track circuit to open a controlling circuit for the signal guarding the portion of track, over which said track circuit extends, upon a failure of current at the far end of said circuit from the source at the other end, each of the signals guarding a length of track corresponding to two track circuits and controlled by two of said sets of contacts.

34. In combination with a railway having both rails conductively continuous for all currents, a block signal system comprising sources of alternating current connected across the rails at intervals, adjacent sources being of different character, connections from one rail to the other between adjacent sources, each set of connections forming with the adjacent sources and the rails between them a pair of closed track circuits, each of said sources being common to two adjacent track circuits, signal controlling circuits, a set of contacts, one for each track circuit, included in said signal controlling circuits, each set of contacts being controlled by current in its track circuit from the source for that circuit only, and signals controlled by the signal controlling circuits.

35. In combination with a railway having both rails conductively continuous for all currents, a block signal system comprising sources of alternating current connected across the rails at intervals, adjacent sources being of different character connections from one rail to the other between adjacent sources, each set of connections forming with the adjacent sources and the rails between them a pair of closed track circuits, each of said sources being common to two adjacent track circuits, signal controlling circuits, a set of contacts, one for each track circuit, included in said signal controlling circuits, each set of contacts being controlled by current in its track circuit from the

source for that circuit only and signals controlled by the signal controlling circuits, the controlling circuits for each signal including two of said sets of contacts.

36. In a block signal system, in combination with a railway having both rails conductively continuous for all currents, signals for the blocks, sources of alternating current connected across the rails at intervals, adjacent sources being of different character and track relays controlling the signals each having a winding supplied with current from the rails, said relays being arranged in pairs between adjacent sources, and the two relays of each pair being responsive respectively to currents from the two adjacent sources whereby one relay of each pair is deenergized by a car at any point between said relay and one adjacent source and the other relay by a car at any point between it and the other adjacent source.

37. In a block signal system, in combination with a railway having both rails conductively continuous for all currents, sources of alternating current connected across the rails at intervals corresponding to the lengths of the blocks, adjacent sources being of different character, track relays each having a winding supplied with current from the rails, said relays being arranged in pairs between adjacent sources, and the two relays of each pair being responsive respectively to currents from the two adjacent sources whereby one relay of each pair is deenergized by a car at any point between said relay and one adjacent source and the other relay by a car at any point between it and the other adjacent source, and signals for the blocks each controlled by two track relays.

38. In a block signal system, in combination with a railway having both rails conductively continuous for all currents; signals for the blocks, sources of alternating current connected across the rails at intervals, adjacent sources being of different character and track relays controlling the signals each having a winding supplied with current from the rails, said relays being arranged in pairs between adjacent sources, each relay being responsive to the current from one adjacent source only and the two relays of each pair being responsive to current from the two adjacent sources respectively, whereby one or the other of said relays is deenergized by a car at any point on the track between said sources.

39. In a block signal system, in combination with a railway having both rails conductively continuous for all currents, sources of alternating current connected across the rails at intervals corresponding to the lengths of the blocks, adjacent sources being of different character, track relays each having a winding supplied with current

from the rails, said relays being arranged in pairs between adjacent sources, each relay being responsive to current from one adjacent source only and the two relays of each pair being responsive to current from the two adjacent sources respectively, whereby one or the other of said relays is deenergized by a car at any point on the track between said sources, and signals for the blocks each controlled by two track relays.

40. In combination with a railway having both rails conductively continuous for all currents, a block signal system comprising signals for the blocks, sources of alternating current connected across the rails at intervals, adjacent sources being of different character, and track relays controlling the signals, a pair of said relays being placed near each other between adjacent sources, each relay having a winding supplied with current from the rails and a second coöperating winding supplied independently of the track circuits with current of such character as to cause the relay to respond to clear a signal only when the track winding is supplied with current from a certain one of the adjacent sources and the two relays of each pair responding to current from the two sources respectively.

41. In combination with a railway having both rails conductively continuous for all currents, a block signal system comprising sources of alternating current connected across the rails at intervals, adjacent sources being of different character, track relays controlling the signals, a pair of said relays being placed near each other between adjacent sources, each relay having a winding supplied with current from the rails and a second coöperating winding supplied independently of the track circuits with current of such character as to cause the relay to respond to clear a signal only when the track winding is supplied with current from one adjacent source and the two relays of each pair responding to current from the two sources respectively, and signals for the blocks each controlled by two track relays.

42. A railway block signal system comprising a railway both track rails of which are conductively continuous for all currents, sources of alternating signaling current connected across the track rails at intervals, track relays supplied with signaling current from the track rails, said relays being grouped in pairs and one pair being placed between each two adjacent sources, and signals for the blocks controlled by said relays, each relay controlling the signal which guards the portion of track between said relay and one adjacent source.

43. A railway block signal system comprising a railway both track rails of which are conductively continuous for all currents, sources of alternating current connected

across the track rails at intervals corresponding to the length of a block, track relays grouped in pairs one pair being placed between each two adjacent sources, each relay 5 having a winding supplied with current from the track rails and a second co-operating winding supplied with current independently of the track circuits, and signals for the blocks controlled by said relays, each 10 relay controlling the signal which guards the portion of track between such relay and one adjacent source, and each signal being controlled by two track relays.

44. In combination with a railway having both rails conductively continuous for all currents, a block signal system, comprising signals for the blocks, controlling circuits therefor, sources of alternating current connected across the track rails at intervals, 15 connections from one rail to the other between adjacent sources, each set of connections forming with the adjacent sources and the rails between them a pair of closed track circuits, each of said sources being common 20 to two adjacent track circuits, and an independent set of signal controlling contacts for each track circuit, means interposed in the said connections and controlling the contacts to cause the said contacts for each track circuit to open a controlling circuit for the signal 25 guarding the portion of track, over which said track circuit extends, upon a failure of current at the far end of said circuit from the source at the other end.

45. In combination with a railway having both rails conductively continuous for all currents, a block signal system, comprising signals for the blocks, controlling circuits therefor, sources of alternating current connected across the track rails at intervals, 30 connections from one rail to the other between adjacent sources, each set of connections forming with the adjacent sources and the rails between them a pair of closed track circuits, each of said sources being common 35 to two adjacent track circuits, and an independent set of signal controlling contacts for each track circuit, means interposed in the said connections and controlling the contacts to cause the said contacts for each track circuit to open a controlling circuit for the signal 40 guarding the portion of track, over which said track circuit extends, upon a failure of current at the far end of said circuit from the source at the other end, each of the 45 signals guarding a length of track corresponding to two track circuits and controlled by two of said sets of contacts.

46. In combination with a railway having both rails conductively continuous for all currents, a block signal system comprising sources of alternating current connected across the rails at intervals, connections 50 from one rail to the other between adjacent sources, each set of connections forming

with the adjacent sources and the rails between them a pair of closed track circuits each of said sources being common to two adjacent track circuits, signal controlling circuits, sets of contacts, one set for each 55 track circuit, included in said signal controlling circuits, each set of contacts being controlled by current in its track circuit from the source for that circuit only, and signals controlled by the signal controlling 60 circuits.

47. In combination with a railway having both rails conductively continuous for all currents, a block signal system comprising sources of alternating current connected 65 across the rails at intervals, connections from one rail to the other between adjacent sources, each set of connections forming with the adjacent sources and the rails between them a pair of closed track circuits, each of said sources being common to two adjacent track circuits, signal controlling 70 circuits, sets of contacts, one set for each track circuit, included in said signal controlling circuits, each set of contacts being controlled by current in its track circuit from the source for that circuit only and signals controlled by the signal controlling 75 circuits, the controlling circuits for each signal including two of said sets of contacts. 95

48. In a block signal system, in combination with a railway having both rails conductively continuous for all currents, signals for the blocks, sources of alternating current connected across the rails at intervals, 80 and track relays controlling the signals each having a winding supplied with current from the rails, said relays being arranged in pairs between adjacent sources, and the two relays of each pair being responsive 85 to currents from the two adjacent sources, whereby one relay of each pair is deenergized by a car at any point between said relay and one adjacent source and the other relay by a car at any point between it 90 and the other adjacent source. 100

49. In a block signal system, in combination with a railway having both rails conductively continuous for all currents, sources of alternating current connected across the 105 rails at intervals corresponding to the lengths of the blocks, track relays each having a winding supplied with current from the rails, said relays being arranged in pairs between adjacent sources, and the two relays 110 of each pair being responsive respectively to currents from the two adjacent sources, whereby one relay of each pair is deenergized by a car at any point between said relay and one adjacent source and the other 115 relay by a car at any point between it and the other adjacent source, and signals for the blocks each controlled by two track relays. 120

50. In a block signal system, in combina- 130

tion with a railway having both rails conductively continuous for all currents, signals for the blocks, sources of alternating current connected across the rails at intervals, and 5 track relays controlling the signals each having a winding supplied with current from the rails, said relays being arranged in pairs between adjacent sources, each relay being responsive to the current from one adjacent 10 source only and the two relays of each pair being responsive to current from the two adjacent sources respectively, whereby one or the other of said relays is deenergized by a car at any point on the track between said 15 sources.

51. In a block signal system, in combination with a railway having both rails conductively continuous for all currents, sources of alternating current connected across the 20 rails at intervals corresponding to the lengths of the blocks, track relays each having a winding supplied with current from the rails, said relays being arranged in pairs between adjacent sources, each relay being

responsive to current from one adjacent 25 source only and the two relays of each pair being responsive to currents from the two adjacent sources respectively, whereby one or the other of said relays is deenergized by a car at any point on the track between said 30 sources, and signals for the blocks each controlled by two track relays.

52. In combination, a railway both track rails of which are conductively continuous for all currents, a plurality of sources of alternating signaling currents connected across the track rails at intervals, two track relays connected across the rails intermediate each two sources, the relays of each pair being responsive respectively to currents from 35 each of the adjacent sources, and railway signals controlled by said relays.

In witness whereof I have hereunto set my hand this 4th day of August 1906.

LAURENCE A. HAWKINS.
